CLAIM

The ornamental design for a cooking basket, as shown and described.

DESCRIPTION

FIG. 1 is an upper perspective view of a cooking basket, showing our new design;

FIG. 2 is a lower perspective view of the embodiment shown in FIG. 1;

FIG. 3 is a front view of the embodiment shown in FIG. 1; FIG. 4 is a rear view of the embodiment shown in FIG. 1; FIG. 5 is a side view of the embodiment shown in FIG. 1; FIG. 6 is another side view of the embodiment shown in FIG. 1;

FIG. 7 is a top view of the embodiment shown in FIG. 1; and,

FIG. 8 is a bottom view of the embodiment shown in FIG. 1.

The broken lines in the figures are for environmental purposes only and form no part of the claimed design.

The dash dot lines represent boundary lines between claimed and unclaimed subject matter.

1 Claim, 6 Drawing Sheets

WO	2018007218 A1	1/2018	OTHER PUBLICATIONS		
WO	2018014806 A1	1/2018	Gill et al.; U.S. Appl. No. 16/059,876, filed Aug. 9, 2018; Cooking Device and Components Thereof.		
WO	2018015695 A1	1/2018	Gill et al.; U.S. Appl. No. 16/059,874, filed Aug. 9, 2018; Cooking Device and Components Thereof.		
WO	2017077571 A1	2/2018	Gill et al.; Design U.S. Appl. No. 29/653,847, filed Jun. 19, 2018; Air Diffuser and Air Diffuser With Food Preparation Pot.		
WO	2018018670 A1	2/2018	Notification of Transmittal of the International Search Report of the International Searching Authority, or the Declaration. PCT/US2018/046077, dated Dec. 19, 2018, 7 pages.		
WO	2018023863 A1	2/2018	Notification of Transmittal of the International Search Report of the International Searching Authority, or the Declaration; PCT/US2018/046079; dated Jan. 2, 2019, 7 pages.		
WO	2018024781 A1	2/2018	Notification of Transmittal of the Written Opinion of the International Searching Authority, or the Declaration. PCT/US2018/046077, dated Dec. 19, 2018, 10 pages.		
WO	2018024782 A1	2/2018	Notification of Transmittal of the Written Opinion of the International Searching Authority, or the Declaration; PCT/US2018/046079; dated Jan. 2, 2019, 10 pages.		
WO	2018024783 A1	2/2018	WO2018122652A1; Jul. 5, 2018; English Abstract Only (3 Pages). U.S. Appl. No. 29/679,923, filed Feb. 11, 2019; Restriction Requirement dated May 13, 2020; 8 pages.		
WO	2018026041 A1	2/2018	U.S. Appl. No. 29/679,924, filed Feb. 11, 2019; Restriction Requirement dated May 13, 2020; 8 pages.		
WO	2018026906 A1	2/2018	U.S. Appl. No. 29/659,571, filed Aug. 9, 2018; Restriction Requirement dated Oct. 1, 2019; pp. 1-8.		
WO	2018026928 A1	2/2018	U.S. Appl. No. 29/659,577, filed Aug. 9, 2018; Restriction Requirement dated Oct. 1, 2019; pp. 1-8.		
WO	2018032540 A1	2/2018	U.S. Appl. No. 29/660,495, filed Aug. 21, 2018; Food Preparation Device and Parts Thereof; Notice of Allowance dated Oct. 25, 2019; pp. 1-9.		
WO	2018032541 A1	2/2018	U.S. Appl. No. 29/660,472, filed Aug. 21, 2018; Restriction Requirement dated Oct. 1, 2019; pp. 1-8.		
WO	2018032542 A1	2/2018	U.S. Appl. No. 29/679,920, filed Feb. 11, 2019; User Interface for a Food Preparation Device; Notice of Allowance dated Oct. 23, 2019; pp. 1-10.		
WO	2018032589 A1	2/2018	U.S. Appl. No. 29/679,922, filed Feb. 11, 2019; Restriction Requirement dated May 13, 2020; 8 pages.		
WO	2018032648 A1	2/2018	U.S. Appl. No. 29/659,576, filed Aug. 9, 2018; Restriction Requirement dated May 19, 2020; 8 pages.		
WO	2018037177 A1	3/2018	U.S. Appl. No. 29/653,847, filed Jun. 19, 2018; Restriction Requirement dated May 29, 2020; 7 pages.		
WO	2018040250 A1	3/2018	U.S. Appl. No. 29/653,863, filed Jun. 19, 2018; Restriction Requirement dated Jun. 2, 2020; 7 pages.		
WO	2018041536 A1	3/2018	Ninja Kitchen; "Ninja Foodi: Pro Grill"; Announced Aug. 15, 2019 [online]; Site visited Jun. 15, 2020; 14 pages; Available from Internet URL: https://direct.ninjakitchen.com/16/products/ninja-foodi-grill-ag302/16/microsite/ogxvii/?ppt=2 .		
WO	2018045643 A1	3/2018	U.S. Appl. No. 29/733,284, filed Apr. 30, 2020; Non-Final Office Action dated Jun. 25, 2020; 10 pages.
